UNITED STATES PATENT OFFICE.

BERNARD D. WILLIS, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed May 25, 1922, Serial No. 563,466. Renewed December 18, 1928.

The present invention relates in general to automatic telephone systems, but is concerned more particularly with the provision of means in such systems for handling calls to certain lines which are disconnected, or which are rendered temporarily inaccessible for some reason. In automatic systems, it is the usual practice to connect the normal conductors of disconnected lines to traffic trunks 5 extending to an intercepting operator's position; and when a calling subscriber, or a toll operator, attempts to complete a connection with a disconnected station, the call will be received by the intercepting operator, who will proceed to inform the calling party that the called station is no longer accessible, or that it is accessible under a new number. With an arrangement of this kind it is essential when a call set up by a calling subscriber is 10 intercepted by an operator due to the called line having been disconnected, that no charge be made to the calling subscriber for the call. It is also essential if the call set up has originated at a toll operator's position, that supervision be given to the toll operator regardless of whether the call is extended to a working subscriber's line, or to an intercepting operator.

The principal object of this invention is 15 the provision of an improved, simple, and inexpensive operator's cord circuit to be used in connection with a so called traffic or intercepting trunk, for answering calls originating either at a subscriber's station or at 20 a toll operator's position, and for extending such calls to any desired line if the occasion requires.

Figs. 1 and 2 illustrate a preferred installation.

Referring to Fig. 1 of the drawings, in the upper portion there is shown a cord circuit O having access through the usual plug P, jack J, toll selector E, toll transmission repeater D, second selector F, and the combination toll and regular connector H, to called lines, such as A', and to answering jacks such as J', Fig. 2, in cases where the called line, such as A', has been disconnected.

In the lower portion of Fig. 1 is indicated 25 a local substation A having access through the usual line switch C, first selector E', second selector F', and connector H' to called

lines such as A', the connector H' having access to the same group of called lines as the connector H.

In Fig. 2 is illustrated a cord circuit O' which is used by the intercepting operator for answering calls which have been extended to jacks such as the jack J', and for extending such calls to a desired subscriber's line 60 over jack J' and line switch C'.

The circuit arrangements shown in the upper portion of Fig. 1, with the exception of the line switch C' and the substation A', are fragmentary portions of certain of the drawings shown in the Wicks Patent, No. 1,616,402, issued Feb. 1, 1927. The same reference numbers applied to the various figures of drawings in the above application have been used in the drawing of this application, so that the elements in this application may be readily found in the above reference if desired.

In the lower portion of Fig. 1 is shown a substation of the usual type found in modern telephone systems, and consisting essentially of a transmitter 5, receiver 6, ringer 7, and a calling device S'. The line switch C may be of the usual type, which may be briefly described as a rotary line switch whose wipers have no normal position, and which have movement in a forward direction only. The operation of switches of this character are well known and need not be further described.

The first selector E', the second selector F', and the connector H' are of the same mechanical structure as the switches E, F and H, that is, they are of the Strowger vertical and rotary type, but are wired for operation in accordance with the two wire system of control, and in view of the fact that the circuits for operating switches of this character to extend local connections are well known it is thought that their operation will be 95 clearly understood.

The substation A' and the line switch C' are identical with substation A and the line switch C.

The meter controlling circuit shown associated with the selector E' illustrates diagrammatically the meter controlling arrangement shown in Patent No. 1,304,369, issued to A. J. Ray, May 20, 1919. Any suitable meter

or toll apparatus operated by a reversal of the calling line circuit may be used however.

The cord circuit O', Fig. 2, is similar to the usual type, but has been modified to operate and function so as to properly carry out the object of the invention, as will be described hereinafter.

On the drawing marked Fig. 1, the relays which have slow acting characteristics are noted by the shading on the lower ends of their cores or else by the solid black portion on the upper ends of their cores. The relays which have cores shaded on the lower end are the usual so-called slow acting relays and are slow to fall back but not noticeably slow to pull up. On the other hand, the relays which have their upper ends of their cores shown solid black are slightly slow to pull up in addition to being slow to fall back.

The general object and scope of the invention having been pointed out, and the apparatus involved having been described, the operation will now be set forth more in detail by explaining the setting up of connections from the cord circuit O and the substation A to the operator's position at which calls are answered by use of the cord circuit O'.

It will first be assumed that the toll operator, or the operator having the cord circuit O, desires connection with a certain substation to which the connector H has access, but which has had the service disconnected for some reason or another. Under these circumstances, the normal conductors coming from the connector banks will have been disconnected from the line, as stated hereinbefore, and will be connected by temporary jumpers such as 307 and 276 to a traffic trunk. The operator proceeds by inserting the plug P into the jack J extending to an idle selector E, and throws the key K to associate the calling device S with the line relay 51 of the selector E.

The operator now proceeds to operate the calling device S in accordance with the various digits of the desired called number, thereby successively controlling the line relays 51, 151, and 201, to control their respective switches E, F, and H, to complete the connection in the well known manner.

Upon completing the impulse sending operation, the operator will momentarily actuate the ringing key K so as to unlock the ring cut off relay 205, which was locked up when the connector H was given its first vertical impulse. The initial energizing circuit of relay 205 includes contacts 219, which are closed during the vertical movement of the connector; and the locking circuit includes contacts 236, which are closed while the connector is in use, except when opened by suitable relay means responsive to the actuation of the operator's ringing key, as above mentioned. These circuit arrangements are fully described in

the Wicks application Patent No. 1,616,402, previously referred to. Relay 205, upon restoring, completes a ringing circuit for operating the ring down relay 301 in the traffic trunk, which may be traced as follows: Interrupted generator Gen, resting contact of armature 229 and said armature, wiper 272, bank contact 275, jumper 276, conductor 277, upper winding of the ring down relay 301, upper armature and resting contact of relay 300, conductor 306, jumper 307, bank contact 273, wiper 270, resting contact of armature 277 and said armature, and the upper winding of ring cut off relay 205 to battery. Upon the completion of this circuit the ring down relay 301 is energized, closes a holding circuit for itself at its armature 303, and at armature 304 closes a circuit for the call signal lamp L.

Returning to the cord circuit O, with the key K at normal a circuit may now be traced from ground, resistance 114, resting contact of armature 117 and said armature, lower left hand winding of the repeating coil R, bank contact 77, and wiper 73 back over the ring side of the cord circuit O, winding of relay 3, tip side of cord circuit O, wiper 70, bank contact 74, upper left hand winding of the repeating coil R, armature 116 and its resting contact, and resistance 112 to battery. Current flow over this circuit results in the operation of the supervisory relay 3, which causes the lamp L' to light.

The operator at the cord circuit O', upon seeing the calling lamp L lighted, answers by inserting the plug P' into the jack J', which completes a circuit from battery, winding of relay 300, sleeve of jack J', sleeve strand of plug P', and resistance X to ground. Relay 300, upon energizing, opens at its upper and lower armatures and back contacts both windings of relay 301. Relay 301 therefore deenergizes and extinguishes the calling lamp L. At the same time, a circuit is completed for the ring cut off relay 205 which may be traced as follows: from ground, resting contact of armature 311 and said armature, winding of impedance coil 310, tip of plug P', tip spring of jack J', conductor 306, jumper 307, bank contact 273, wiper 270, armature 277 and its resting contact, and the upper winding of ring cut off relay 205 to battery. The operation of relay 205 disconnects the generator at its armature 229, and at the same armature and armature 277 extends the trunk line directly to the jack J'. In addition, at its armature 228 relay 205 closes a locking circuit for itself to the release trunk, in a well known manner. As a further result of the energization of relay 205, a circuit is completed for the battery feed relay 100, which is substituted for the upper winding of relay 205 in the circuit above traced extending over the tip side of the traffic trunk and through impedance coil 310 at cord circuit O' to ground.

Relay 100 is accordingly energized and at its armatures 116 and 117 disconnects battery and ground from the conductors leading back to the supervisory relay 3 of the cord circuit O. Relay 3 deenergizes and extinguishes the lamp L', thus giving the toll operator answering supervision.

The toll operator may now throw her key K to listening position and on finding that 10 the answering party is an intercepting operator she will give such operator the number of the called party and will in turn be advised by the intercepting operator as to the condition of his line. If the desired subscriber has been permanently disconnected, 15 the toll operator may so inform the calling party, but should the called subscriber's number merely have been changed, the toll operator will set up the connection in the usual 20 manner in accordance with the changed number. The intercepting operator after giving the toll operator the desired information removes the plug P' from the jack J', which will cause the relay 100 of the toll transmission repeater to be deenergized. If the toll operator has not withdrawn the plug P, a 25 circuit will again be completed for the relay 3 in the cord circuit O, this time causing the lamp L' to light, to indicate to the toll operator that a disconnection is desired, whereupon she will withdraw the plug P and cause the various switches to be restored in the usual manner.

It will now be assumed that the connection 35 has been set up from the substation A. In this case the various switches C, E', F', and H' will have been operated in the usual manner to extend the connection to the jack J'. The ringing operation, although automatically initiated, will be similar to that previously described. When the intercepting operator inserts the plug P' into the jack J', a circuit is completed through the impedance coil 310 and the ring cut off relay 205'. After the operation of relay 205', a circuit is completed from ground, winding of impedance coil 310, tip of plug P', tip strand of jack J', conductor 306, jumper 307, bank contact 273', wiper 270', armature 277' and its working contact, and the upper winding of back bridge relay 200 to battery. At the same time another circuit is completed from ground, lower winding of back bridge relay 200, armature 229' and its working contact, wiper 272', bank contact 275', ring spring of jack J', ring of plug P', winding of impedance coil 312, armature 305 and its resting contact, to positive battery and ground. Owing to the fact that the current now flows in opposite directions in the two windings of back bridge relay 200, a differential effect is produced, and the relay will not energize. No reversal of current flow in the calling line circuit will take place, therefore, and 60 consequently the polarized meter magnet 24

associated with the first selector E' will not be operated.

The intercepting operator operates her listening key K' as before, and proceeds to inform the calling subscriber of the disconnection or change in number of the desired party. If the desired party has been disconnected from service, the calling subscriber replaces the receiver, causing the switching apparatus to be restored in the usual manner.

It may be, however, that the called subscriber's telephone number has merely been changed. Under these circumstances, the intercepting operator will inform the calling subscriber of the new number, after which the subscriber may momentarily hang up his receiver and then proceed to set up the connection in accordance with the new number, or the operator may complete the connection for the subscriber. Under the latter condition the operator inserts the calling plug P² into an idle jack, such as J², connecting the polarized relay 308 in bridge of the trunk. This completes an operating circuit for the line switch C², which operates to hunt for and seize an idle trunk line. When the plug P² is inserted in the jack J² a circuit is also completed for the relay 313. Relay 313 operates to complete a circuit for the supervisory signal L². The operator then throws the calling device key K² to substitute the calling device S² for the polarized relay 308.

The operator now proceeds to set up the connection in the usual manner, and after dialling the complete called number restores the key K² to normal, thereby again inserting the relay 308 in bridge of the line. When the called subscriber answers the current flow is reversed in the usual manner, causing the polarized relay 308 to operate. The operation of the polarized relay 308 breaks at its upper armature the circuit for the lamp L², and at its lower armature completes a circuit for the relay 307. Relay 307 operates, disconnecting at its upper and lower armatures ground and positive battery from the previously described back bridge relay 200 in the connector H', and at the front contacts of these armatures completes a direct bridge across the tip and ring strands of the cord. The relay 200 now operates, causing the current flow in the calling line to be reversed, resulting in the operation of the meter control relay 24. Although shown as a simple polarized relay, in actual practice relay 24 would be an electro-polarized relay of the type shown in the Ray patent, previously referred to. The operation of the relay 24 completes the operating circuit of meter magnet MM to charge for the call, in the same manner as if the call had been directly set up by the calling subscriber. When the conversation is completed the called subscriber upon replacing his receiver causes the polarized relay 308 to

deenergize, again completing the circuit for the lamp L^2 and thus notifying the intercepting operator that a disconnection is desired.

Should the call have originated at an information operator's position, the intercepting operator would have set up the connection in the same manner as has been explained for a subscriber. In this case instead of operating a meter, the information operator's and the intercepting operator's supervisory lamps would be extinguished when the called subscriber answered, these lamps again lighting when a disconnection was desired.

What is claimed is:

1. In a telephone system, a traffic trunk, two trains of switches by means of which calls may be extended to said trunk, a battery feed relay bridged across the talking conductors at one of the switches in each train, an operator's link circuit adapted to be connected with said trunk to answer calls received thereover, and circuit connections in said link circuit adapted to cause the energization of the associated battery feed relay in case a call is answered which has been extended over one of said switch trains, but adapted to prevent the energization of the associated battery feed relay in case a call is answered which has been extended over the other switch train.

2. A system according to claim 1, in which one of the battery feed relays is single wound and the other double wound, and in which the double wound relay is prevented from operating by the differential effect of currents flowing through its two windings in opposite directions.

3. A system according to claim 1, in which one of the battery feed relays is single wound and the other double wound, in which the double wound relay is prevented from operating by the differential effect of the currents flowing through its two windings in opposite directions, and in which the link circuit includes a battery of opposite polarity to the main exchange battery for causing the differential action at the double wound battery feed relay.

4. In a telephone system, a temporarily established connection including a subscriber controlled connector switch, a trunk line, and an operator's cord circuit, a double wound back bridge relay connected across the talking conductors at said connector in series with a battery, a circuit for one winding of said relay including the said battery, a conductor of said trunk line, and one strand of said cord circuit, and a second circuit for preventing the energization of said relay, said second circuit including another conductor of said trunk line, another strand of said cord circuit, and a battery associated with the cord circuit of opposite polarity to said first battery.

5. In a telephone system, a temporarily established connection including a subscriber

controlled connector switch, a trunk line, and an operator's cord circuit, a double wound back bridge relay connected across the talking conductors at said connector in series with a battery, a circuit for one winding of said relay including the said battery, a conductor of said trunk line, and one strand of said cord circuit, a second circuit for preventing the energization of said relay, said second circuit including another conductor of said trunk line, another strand of said cord circuit, and a battery associated with the cord circuit of opposite polarity to said first battery, means for extending the connection to a called line, a relay in said cord circuit controlled by the called subscriber, and contacts controlled by said relay for clearing both strands of the cord circuit of their normal battery connections and for closing a bridge across said strands to energize the said back bridge relay.

6. In a telephone system, a subscriber's line, an operator's position, a trunk terminating at said position, a first and a second automatic switch having access to said line and said trunk for extending calls either to said line, or said operator's position via said trunk, answering responsive means in each of said switches operative when a call is extended to said subscriber's line and is answered by the called subscriber, a cord circuit at said operator's position for answering calls extended thereto, and means in said cord circuit for operating the answering responsive means in said first switch when a call extended to said operator's position via said first switch is answered by the operator and for preventing the operation of the answering responsive means in said second switch when a call extended to said operator's position via said second switch is answered by the operator.

7. In a telephone system, a subscriber's line, an operator's position, a trunk terminating at said position, a first and a second automatic switch having access to said line and said trunk for extending calls either to said line, or said operator's position via said trunk, answering responsive means in each of said switches operative when a call is extended to said subscriber's line and is answered by the called subscriber, a cord circuit at said operator's position for answering calls extended thereto, means in said cord circuit for operating the answering responsive means in said first switch when a call extended to said operator's position via said first switch is answered by the operator and for preventing the operation of the answering responsive means in said second switch when a call extended to said operator's position via said second switch is answered by the operator, means including said cord circuit for further extending a call extended to said position via said second switch to said subscriber's line, and means in said cord circuit operative responsive to the answering of the call by the called subscriber.

for operating said answering responsive means in said second switch.

8. In a telephone system, a connector, an operator's position, a subscriber's line and a trunk terminating at said position accessible to said connector, means for operating said connector to extend a connection to said line or to said trunk, means at said position for extending a connection from said trunk to said line, and answering responsive means in said connector operable when the subscriber on said line answers the call irrespective of whether the call has been extended to said line from said connector directly or from said connector via said operator's position.

9. In a telephone system, a connector, an operator's position, a subscriber's line and a trunk terminating at said position accessible to said connector, means for operating said connector to extend a call to said line or to said trunk, answering responsive means in said connector operable when a call extended to said line via said connector is answered by the called subscriber, a cord circuit at said operator's position for answering calls extended thereto, means in said cord circuit for preventing the operation of the answering responsive means in said connector when a call extended to said position via said connector is answered by the operator, means including said cord circuit for extending a call from said position to said line, and means in said cord circuit for operating said answering responsive means in said connector when a call extended to said line via said connector and said cord circuit is answered by the called subscriber.

10. In a telephone system, a calling line, a meter, a called line, an operator's position, means for extending a call from said calling line to said called line or to said position, means for operating said meter when a call extended from said calling line to said called line is answered by the called subscriber, means for preventing the operation of said meter when a call extended to said position is answered by the operator, means at said position for extending a call extended thereto to said called line, and means for operating said meter when a call extended from said calling line to said called line via said position is answered by the called subscriber.

11. In a telephone system, a calling line, a meter, a called line, an operator's position, means for extending a call from said calling line to said called line either exclusive of any operator's position or via said position, and means for operating said meter when a call extended from said calling line to said called line over either route is answered by the called subscriber.

12. In a telephone system, an operator's cord circuit comprising two sections, a bridge including a battery normally across one section of said cord circuit, a called line, means

for extending a connection to said line via said cord circuit, and a polarized relay bridged across the other section independent of said battery and operative when the called subscriber answers the call for excluding said battery from said bridge.

13. In a telephone system, an operator's cord circuit, a bridge including a battery normally bridged across the talking conductors of said cord circuit, a called line, means including an automatic switch for extending a connection to said line via said cord circuit, and means operative when the called subscriber answers the call for excluding said battery from said bridge.

14. In a telephone system, an operator's cord circuit comprising two sections, a bridge including a battery normally across one section of said cord circuit, a called line, means for extending a connection to said line via said cord circuit, said connection including an automatic switch between the cord circuit and the called line, and a relay bridged across the other section of said cord circuit and operative when the called subscriber answers the call for disconnecting said normal bridge and connecting another bridge across said one section excluding said battery.

15. In a telephone system, a connector, an operator's position, a subscriber's line and a trunk terminating at said position accessible to said connector, means for operating said connector to extend a connection to said line or to said trunk, means at said position for extending a connection from said trunk to said line, and a meter responsive when the subscriber on said line answers the call irrespective of whether the call has been extended to said line from said connector directly or from said connector via said operator's position.

16. In a telephone system, a calling line, an operator's position, a directly controlled automatic switch common to said calling line and other lines, means including said automatic switch for extending a connection from said calling line to said operator's position, a called line, means at said operator's position for further extending the connection to said called line, means responsive when the call is answered by the called subscriber, and a meter responsive to the operation of said last means.

17. In a telephone system, a calling line, an automatic switch common to said line and other lines, an operator's cord circuit, a called line, means for extending a connection from said calling line to said called line via said switch and said cord circuit, means in said switch responsive when the called subscriber on the called line answers the call, and a meter individual to said line and responsive to the operation of said last means.

18. In a telephone system in which connections to called lines are established by way

of an automatic switch having a double wound back-bridge relay which is operated when a call is answered by the establishment of a flow of current in the two windings in the same direction, and in which calls to disabled lines are trunked to an operator's position, means responsive when a call trunked

to an operator's position is answered by the operator for establishing a flow of current in the two windings in opposite directions to prevent the operation of said relay.

In witness whereof, I hereunto subscribe my name this 19th day of May, A. D. 1922.

BERNARD D. WILLIS.
